United States Patent

Des. 235,514
Patented June 24, 1975

235,514

CARTON

Robert A. Hackenberg, East Lyme, Conn. (½ Robertson
Paper Box Co., Inc., Montville, Conn. 06353)

Filed Aug. 28, 1972, Ser. No. 284,368

Term of patent 7 years

Int. Cl. D9—03

U.S. Cl. D9—224

FIG. 1

FIG. 3

FIG. 2

FIG. 4

FIG. 5

FIG. 6

FIG. 1 is a perspective view of a carton embodying my new design;

FIG. 2 is a side view thereof;

FIG. 3 is a rear view thereof;

FIG. 4 is a top view thereof;

FIG. 5 is a bottom view thereof; and

FIG. 6 is a front view thereof.

I claim:

The ornamental design for a carton, substantially as shown.
